POURING SPOUT

Alexander Parsons, Minneapolis, Minn., assignor to Pillsbury Flour Mills Company, Minneapolis, Minn., a corporation of Delaware

Application April 19, 1941, Serial No. 389,408

2 Claims. (Cl. 221—11)

This invention relates to pouring spouts for containers, and particularly to the general type of trough-shaped spout which is hingedly connected with an apertured portion of a container and has its body or trough bottom constructed to close the container aperture when swung inwardly.

Such spouts have been extensively used in containers constructed of sheet metal, cardboard and other sheet material.

In many instances the body of the trough-like member has been hingedly associated with, but not attached to, a lip projecting from one of the short ends of the apertured portion of the container. With sheet metal and relatively stiff cardboard containers such structures have been quite satisfactory, but with container walls constructed of relatively flexible material such as thin cardboard, the lip and other edges of the wall defining the aperture usually weaken or flex with repeated use of the spout, with the result that such spouts often become displaced or detached either inwardly or outwardly of the container.

In some instances where containers of more flexible material, such as relatively thin cardboard, were utilized, parts of the spout were crimped or clipped to an edge of the apertured portion of the container forming a permanent connection to provide a hinge axis. Such permanent connection, however, required machinery, special tools or hand operations, increasing the cost of manufacture and assembly of the container and spout.

It is an object of my invention to provide a pouring spout for containers of sheet wall construction, and particularly adapted for containers having relatively flexible walls such as the cardboard containers extensively used in packaging granular food products, whereby an efficient hinge connection is obtained between the spout and apertured container wall without requiring the securing together of the parts, while, nevertheless, eliminating displacement or detachment of the spout inwardly or outwardly of the container during normal use thereof.

A further object is the provision of a spout of the class described in the preceding paragraph which may be manufactured very inexpensively and which may be quickly and easily attached and sprung into position in a container opening without the use of any mechanical means.

More specifically, it is an object to provide an integrally formed, hinged pouring spout for relatively thin containers which is so constructed

that its hinge connection with and retention in an apertured container wall is not dependent upon the rigidity or wearing qualities of a lip or tab or other edges of the container which define the discharge opening, but on the other hand is provided with abutment means on the side edges of the body adjacent the hinge axis for preventing inward displacement of the spout, and is further provided with means also adjacent the hinge axis for abutting the inner wall of the apertured container both in the fully open and closed positions of the spout to prevent outward displacement.

These and other objects and advantages of the invention will be more fully set forth in the following description made in connection with the accompanying drawing, in which like reference characters refer to the same parts throughout the several views, and in which:

Fig. 1 is a fragmentary side elevation of the upper portion of a package or relatively thin cardboard container having an embodiment of my improved spout applied thereto;

Fig. 2 is a fragmentary vertical section taken on the line 2—2 of Fig. 1, with the spout in its closed position;

Fig. 3 is a similar vertical section with the spout in its open or pouring position;

Fig. 4 is a plan view of the blank from which my improved spout is formed;

Fig. 5 is a perspective view showing the completed pouring spout formed from the blank shown in Fig. 4, and

Fig. 6 is a fragmentary plan view showing the wall of the container and the construction of the discharge opening formed therein for reception of the spout.

My improved pouring spout is preferably constructed integrally from a sheet of thin material, such as non-corrosive sheet metal having some degree of resiliency. The shape of the blank is clearly shown in Fig. 4. Such blanks may be very inexpensively and rapidly die-cut from flat sheet material.

My improved spout is of general trough shape having a flat, substantially rectangular body 7 having straight, longitudinal side edges 7a, a straight bottom edge 7b extending substantially perpendicular to said side edges, and an upper, preferably convexly curved edge 7c which forms a finger piece by which the spout may be swung from closed to open position. A pair of sector-shaped wings 8 extend substantially perpendicularly from the longitudinal edges of the spout body having their curved edges 8a disposed sub-

stantially concentrically of the lower edge $7b$ of the spout which represents approximately the hinge axis. The lower or straight edges $8b$ of the wings 8 , as shown, lie substantially in a plane with the lower edge $7b$ of the spout body, although this relationship may be varied considerably, all within the scope of the invention. Extending from said edges $8b$ of each of the wings are forward and rear abutment lugs $8c$ and $8d$, respectively, both extending perpendicularly to the plane of the wing, and the forward abutment lug $8c$, as clearly shown in Figs. 4 and 5, having its forward edge substantially aligned or very slightly disaligned from the adjacent longitudinal edge $7b$ of the spout body. The rear abutment lug $8b$ of each wing is preferably positioned adjacent the outer free corner of the wing, although it may be spaced somewhat forwardly thereof or, if desired, a continuous flange may be substituted for lugs $8c$ and $8d$ extending substantially the full length of the wing edges $8b$.

The body 7 of the spout is provided adjacent the lower or hinge edge $7b$ with a pair of outwardly and laterally projecting abutment lugs $7d$, which may be conveniently struck up from the stock of the adjacent portions of the wings and which lie preferably in the plane of the body 7 .

While the trough-shaped spout, as shown, has a substantially rectangular body 7 with parallel sides $7a$, it will be understood that the sides $7a$ may taper from the hinge edge $7b$ to the finger piece end $7c$.

A discharge aperture 9 is formed in a wall of the container for reception and accommodation of the spout of substantially the general shape of the spout body 7 , but preferably having a straight, short edge $9a$ at one end of the opening adapted to be overlapped slightly by the convexly curved finger piece $7c$ of the spout, and preferably, although not necessarily, having a concavely curved, upwardly extending lip $9b$ at the opposite end of the opening against which the hinge edge $7b$ of the spout is adapted to bear to facilitate the hinge action.

My spout, as constructed in Fig. 5, may be quickly and easily applied to the container before or after the same is packed, by first engaging the longitudinal edges $9c$ defining the container discharge opening between the respective abutment lugs $7d$ and $8c$ of the spout. This is facilitated by inclining the lower portion, including edge $7b$ of the spout, relatively to aperture 9 and then twisting the spout to properly dispose said abutment lugs with lugs $7d$ on the exterior of the wall and with lugs $8c$ engaging the interior of the wall. Thereafter the wings 8 are sprung together slightly to permit the rear abutment lugs $8d$ to pass the side edges $9c$ of the opening and be disposed on the interior of the wall. The spout is then disposed in the open position shown in Fig. 3 and may be readily swung to the closed position shown in Fig. 2 with the body 7 completely covering the aperture and with the finger lip $7c$ slightly overlapping the upper edge of the opening $9a$. If desired, and as shown in Fig. 1, the thin label or wrapping L of the package may be adhesively applied to the container proper after the spout has been attached, thereby completely covering the body 7 of the spout and insuring the spout against any outward displacement during shipping or handling. As shown, the words "Spout under here" are printed on the label directly above the spout to indicate that the thin wrapper may be torn with

the finger, the lip $7c$ engaged and the spout rendered accessible for use. In the closed position, it will be noted (see Figs. 1 and 2) that the lugs $7d$ extending laterally from the body of the spout, 5 abut against the outer surface of the apertured container wall, positively preventing inward disconnection or dislocation of the spout adjacent the hinge edge $7b$. The finger piece $7c$ at the upper end of the spout body prevents inward displacement of that part. In this closed position it will further be noticed that the forward edges of the lugs $8c$ engage against the inner surface of the apertured container wall, positively preventing outward displacement of the spout. The spout hinges in its opening movement on the edge $7b$ and to some extent on the 10 said forward edges of the lugs $8c$, in the form of container opening disclosed the hinged edge $8b$ fulcruming upon the lip $9b$ defining the lower 15 end of the aperture. In fully opened position (see Fig. 3) the flat upper surfaces of the forward lugs $8c$ on the wings engage against the inner surfaces of the container wall, as also do the flat surfaces of abutment lugs $8d$, thereby 20 positively preventing outward displacement of the spout during the pouring operation. Simultaneously the lower edges of the lugs $7d$ are spaced a slight distance outwardly of the external 25 wall of the container, but will positively prevent inward displacement of the spout during the pouring operation. The close cooperation between the abutment lugs $7d$ and $8c$, as has been set forth, provides a novel and extremely efficient means for attaching the spout to permit 30 hinge action thereof in a container wall with elimination of any chance of detachment or dis- 35 placement of the spout, both inwardly and outwardly, during continuous use of the device. The said structure permits an efficient spout to be 40 readily attached to containers having relatively thin and flexible walls without the use of clips, fasteners, crimping or other permanent connection means at the hinge portion of the spout.

In forming my improved spout from the blank 45 shown in Fig. 4, it will be apparent that the sector wings 8 are bent from the body 7 on the dotted fold lines X , such bending leaving the cut or struck-out lugs $7d$ extending in the same plane with the body 7 . The lugs $8c$ and $8d$ are 50 bent outwardly from the straight edge of the wing portions to be disposed in a plane or planes substantially perpendicular to the respective planes of the wings 8 .

It will, of course, be understood that various 55 changes may be made in the form, details, arrangement and proportions of the parts without departing from the scope of my invention, which, generally stated, consists in a device capable of carrying out the objects above set forth and in 60 the novel parts and combinations of parts disclosed and defined in the appended claims.

What is claimed is:

1. In combination with a container having a four-sided discharge opening in a wall thereof, 65 said opening having a lip extending therein from one of its sides, a pouring spout of trough shape having a central body shaped to close said opening and provided with sector-shaped side wings, the lower edge of said body being straight and constituting the hinge axis of said spout, said lower edge engaging and fulcruming upon the lip in said discharge opening, the curved edges of said wings being substantially concentric with the hinge axis of said spout, said wings on their edges which extend from the hinged portion of

said spout having aligned, substantially perpendicular projections extending outwardly and having edges disposed substantially in alignment with said lower edge of said central body, said edges engaging the inner wall of the container when the spout is in closed position and fulcruming on said inner wall during opening of said spout and the faces of said projections engaging the inner wall of the container when said spout is in open position, and a pair of abutment elements projecting laterally from the wing adjacent sides of said body and lying in the plane of said body for engagement with the outer surfaces of said wall in the closed position of said spout.

2. In combination with a container having a quadrilateral discharge opening formed in a wall thereof, said wall having a convexly curved lip extending into said opening and defining one of the edges thereof, a pouring spout of trough shape having a central quadri-lateral body shaped to close said opening and provided with sector-shaped side wings extending substantially perpendicular to said body, the lower edge of

said body being straight and constituting the hinge axis of said spout and engaging and fulcruming upon said lip with the lower edges of said wings accommodated in said opening at the sides of said lip when said spout is closed, the curved edges of said wings being substantially concentric with the hinge axis of said spout, said wings at their lower edges immediately adjacent the lower edge of said body having aligned, substantially perpendicular projecting lugs extending outwardly and having edges disposed substantially in alignment with said lower edge of said body and engaging the inner wall of the container when the spout is in closed position and fulcruming thereon during the opening of said spout and the faces of said projections engaging the inner wall of the container when said spout is in open position, and a pair of abutment elements projecting laterally from the wing-adjacent sides of said body and lying in the plane of said body for engagement with the outer surface of said wall in the closed position of said spout.
